UNITED STATES PATENT OFFICE.

FRANCIS H. MONTREUIL, OF CHICAGO, ILLINOIS, ASSIGNOR TO WARREN WEBSTER & COMPANY, A CORPORATION OF NEW JERSEY.

CONSERVING-VALVE.

1,268,597.

Specification of Letters Patent. Patented June 4, 1918.

Application filed September 6, 1916. Serial No. 118,663.

To all whom it may concern:

Be it known that I, FRANCIS H. MONTREUIL, a citizen of the United States, and resident of Chicago, county of Cook, and State of Illinois, have invented an Improvement in Conserving-Valves, of which the following is a specification.

The object of my invention is to provide an efficient construction of conserving valve 10 for steam heating systems adapted for maintaining an initial operative pressure on the steam supply side of the valve by automatically shutting off the delivery of steam to the heating system until the said initial 15 pressure builds up to or in excess of the predetermined minimum pressure under which the heating system is to operate, whereby the operation of the vacuum pump of the system shall be assured and the internal 20 condition of the system required shall be present when the steam is admitted thereto.

My object is also to provide a suitable construction of conserving valve which shall, 25 during the operation of the heating system, cause the vacuum pump to be initially operated under a predetermined differential in pressure, the steam to operate the pump being taken from the steam main on the inlet 30 side of the conserving valve, and the exhaust of the steam cylinder of the pump being delivered into the steam main on the outlet side of the conserving valve and leading to the radiators of the heating system, so that 35 the vacuum pump is normally operated, irrespective of the variable pressure under which the steam may be supplied to the system, after once being in full operation to provide a partial vacuum.

40 My object is also to provide a construction of conserving valve of simple and inexpensive character and capable of adjustment for adaptation to a heating system under usual variable conditions, the differential 45 under which the valve is to operate being that between the initial steam pressure and atmospheric pressure supplemented by adjustable mechanical devices such as a weight, or a weight associated with a spring.

50 With the above and other objects in view, the nature of which will be more fully understood from the description hereinafter, the invention consists in the novel construc-

tion of conserving valve as hereinafter more fully described and defined in the claims. 55

Referring to the drawings: Figure 1 is a sectional elevation of a conserving valve embodying my invention; Fig. 2 is a plan view of the same; and Fig. 3 is a diagrammatic view illustrating the adaptability of 60 my improved valve to a steam heating system.

The valve body 2 is provided with an inlet port 3 and an outlet port 4, and with a thoroughfare divided by a partition 5 having the valve seats 6 and 7. Valves 8 and 9, secured together and having wing guide portions 10, are respectively adapted to the seats 6 and 7 and coöperate as a balanced valve device. The lower part of the body 70 2 is closed by a bottom plate 2^b. The upper part of the body 2 is covered by a bonnet plate 2^a. The valve stem 11 of the valves is extended upward and loosely through a hole 16 of the bonnet plate. The stem 11 75 within the body and between the valve 8 and bonnet plate 2^a is provided with a disk 17 having secured to its perimeter the lower end of a bellows member 18, the upper end of which is secured to an annular plate 23 80 tightly clamped between the body and bonnet to form a steam tight joint. From this construction it will be observed that the valves 8 and 9 are substantially balanced, and the under side of the disk 17 of the 85 bellows is subjected to the steam pressure of the inlet side, whereas the upper surface of the disk and inside of the bellows is subjected to atmospheric pressure, so that there is a variable differential on opposite sides 90 of the disk 17 according to variations of the steam pressure in the inlet chamber of the conserving valve. The upper end of the valve stem 11 is jointed to the lever 12, said lever hinged by links 13 to the bonnet plate 95 2^a and having its free end provided with an adjustable counterweight 14, whose position on the lever determines the amount of pressure applied to close or tend to close the valve. This lever is also guided by the 100 slotted bracket 13^a extending upward from the bonnet plate to steady the lever and prevent lateral strain upon the valve stem 11. A spring 19 is arranged to assist the gravity action of the weight; it has its upper 105 end connected with the lever 12 and its

lower end connected with a screw threaded rod 20 which passes through a hole 21^a in the flange 21 of the bracket, and drawn down by a nut 22, by which the desired 5 tension may be put upon the spring. This spring is preferably of relatively small power as compared to the gravity action of the weight 14, and its function permits of an accurate adjustment of the opposing 10 forces to the actuating steam pressure under which the valve automatically operates. The operation of the spring 19 is not so much to provide a tension to assist in keeping the valve closed, as it is to retard the 15 action of the final movements of the parts in fully opening the valve and prevent violent action in opening. An adjustable stop screw 13^b is carried in the upper end of the bracket 13^a to adjust the limit of the upward throw 20 of the lever 12.

The bellows 18 and its disk 17, not only act to obviate the necessity of a stuffing-box and the incident friction thereof, but provide, in effect, a movable diaphragm affected 25 on one side by the internal steam pressure and on the other side by atmospheric pressure assisted by the adjustable mechanical pressure means.

The spring 19 and its screw threaded rod 30 20 may be adjusted farther out on the lever 12 and flange 21, to increase its power, if so desired, this being accomplished by hooking the spring to either of the plurality of holes 12^a in the lever 12 and placing the rod 20 35 in the corresponding hole 21^a of the flange 21. The increased leverage thus provided through which the spring operates, is desirable where the initial steam pressure is relatively high or where the valves 8 and 9 are 40 not as fully balanced as shown, or both.

Referring to Fig. 3, 24 is the steam main leading from the source of steam and connecting with the inlet of the conserving valve 2, and 25 is a steam supply pipe leading 45 from the outlet of the conserving valve to the radiators, one of which is shown at 26. The steam supplied to the radiator is controlled by a hand valve 33. The return pipe is shown at 27, being connected with 50 the radiator by a return valve 32 of any suitable construction which permits the passage of air and water from the radiator into the return pipe but restricts or prevents the passage of steam. 28 is a vacuum pump having 55 its suction connected with the return pipe 27, the discharge of which may be arranged in any suitable well known manner to directly or indirectly return the water of condensation to the boiler as preferred. 60 The steam cylinder 29 of the vacuum pump receives its supply of steam from the steam main 24 and may exhaust into the steam heating supply pipe 25 connecting with the radiators, or otherwise, as desired.

65 It will now be understood that the con-

serving valve is initially closed, and if the valve is adjusted to remain closed until an initial pressure of five pounds is generated, no steam will pass from the boiler to the heating system until this pressure has been 70 reached. Before the steam is supplied to the heating system through the conserving valve, it is supplied to the vacuum pump 28 by the pipe 30 and consequently a partial vacuum is produced in the heating system 75 and the radiators exhausted of air as a preliminary step to the operation of the heating system. When the steam pressure in the main 24 reaches five pounds, the said pressure acting on the under side of the disk 17 80 and bellows raises the stem 11 and its valves 6 and 7 to admit steam to the pipe 25. The valves 8 and 9 open fully and the inertia of the final opening is opposed by the action of the spring 19 which increases its power 85 as the lever 12 is raised. In this way, the lever comes to a stop gradually and objectionable strain is prevented upon the bellows 18.

As the vacuum pump is maintained in 90 operation and the system is cleared of water and air, it is manifest that the heaters or radiators may be made to give out heat to any degree between none and their maximum capacity, dependent upon the adjustment of 95 the steam valve 33.

As the conserving valve is a substantially balanced valve so far as the valves 8 and 9 are concerned, it is immaterial what relative pressures may be in pipes 24 and 25; 100 and the differential under which the conserving valve operates is assured inasmuch as it is dependent upon atmospheric pressure assisted by definitely adjusted mechanical means and wholly independent of variable pressures in the steam heating system 105 *per se*.

If the upper valve 8 be of slightly greater area than the lower valve 9, there will be a corresponding resistance to the opening of 110 the valve, but once the opening movement has begun, the conserving valve as a whole will open quickly under the pressure action upon the under side of the disk 17; but should any such difference in valve areas 115 be employed they are preferably insufficient to interfere with the valve being considered as a substantially balanced valve. In the particular construction shown, the disk 17 is secured in position upon the stem 11 by nuts 120 11^a and lead washers 11^b, but this mode of connection may be varied if so desired.

It should be borne in mind that with the system described, the steam supply to the heater is at all times under automatic 125 throttling control, and with the pump in continuous operation irrespective of the volume or pressure of steam on the outlet side of the conserving valve, the vacuum created by the pump will at times extend 130

through the entire system of piping back to the conserving valve, and the degree of vacuum on the outlet side of said valve will be relatively greater when a minimum volume is passing through the valve, as for instance, when the boiler pressure objectionably drops on account of firing or other conditions. As the steam actuated piston of the pump is receiving the steam from the boiler side of the conserving valve and is exhausting into the system on the heater side of the conserving valve in which the lower pressure exists, it is manifest that the pump will be operating on a differential pressure governed by the pressures on the opposite sides of the conserving valve, and in this way the pump will continue to operate irrespective of material changes in the boiler pressure, thereby making the system automatic and independent of the maintenance of any definite minimum boiler pressure after the system has been put into operation.

The automatic conserving valve is set to open initially and admit steam into the heating system when the pressure on the inlet side exceeds that required to operate the pump; and it remains closed until or after that pressure is reached and thus permits no steam to pass into the heating system until the pump has started and exhausted the air. Consequently, due to this advance operation of the vacuum pump, a partial vacuum may be created within the return system before the steam reaches the radiators, and quicker circulation is established. Inversely, if the boiler pressure should drop, due to irregular firing or to other causes, so that the heating system receives no steam except from the pump exhaust, or if steam is purposely cut off from the heating system, the pump, taking its steam from the high pressure side of the conserving valve, will continue to operate and thus insure the return of all condensation to the boiler, preventing the damage to the boiler which might otherwise occur.

It will be noted that after a partial vacuum has been created throughout the system, the pump will continue to operate in maintaining this vacuum even when the boiler pressure falls below the initial pressure required to start the pump, because, when the heating system is operating on a partial vacuum, the absolute pressure required to operate the pump may be supplied by the differential due to the presence of the conserving valve irrespective of the actual steam pressure in the boiler, and hence the system is operative for the various fluctuations possible in the boiler pressure.

It will now be apparent that I have devised a novel and useful construction of valve which embodies the features of advantage enumerated as desirable, and while

I have in the present instance shown and described the preferred embodiment thereof which has been found in practice to give satisfactory and reliable results, it is to be understood that I do not restrict myself to the details, as the same are susceptible of modification in various particulars without departing from the spirit or scope of the invention.

Having now described my invention, what I claim as new and desire to secure by Letters Patent, is:—

1. In a device of the character stated, the combination of a body having inlet and outlet ports and a thoroughfare between them, a valve to control the thoroughfare having a stem extending to the outside of the case, an expansible member having one part connected with the valve stem to move with it and the other part connected with the body and subjected on one side to the pressure of the atmosphere and on the other side to the pressure within the body on the inlet side to open the valve, and a weighted lever connected to the body and operating upon the valve stem to close the valve against the inlet pressure acting upon the expansible member.

2. In a device of the character stated, the combination of a body having inlet and outlet ports and a thoroughfare between them, a valve to control the thoroughfare having a stem extending to the outside of the case, an expansible member having one part connected with the valve stem to move with it and the other part connected with the body and subjected on one side to the pressure of the atmosphere and on the other side to the pressure within the body on the inlet side to open the valve, and an adjustable weighted lever connected to the body and operating upon the valve stem to close the valve against the inlet pressure acting upon the expansible member.

3. In a device of the character stated, the combination of a body having inlet and outlet ports and a thoroughfare between them, a valve to control the thoroughfare having a stem extending to the outside of the case, an expansible member having one part connected with the valve stem to move with it and the other part connected with the body and subjected on one side to the pressure of the atmosphere and on the other side to the pressure within the body on the inlet side to open the valve, a weighted lever connected to the body and operating upon the valve stem to close the valve against the inlet pressure acting upon the expansible member, and a spring connected with the lever and coöperating with the weight thereof for closing the valve.

4. In a device of the character stated, the combination of a body having inlet and outlet ports and a thoroughfare between them,

a valve to control the thoroughfare having a stem extending to the outside of the case, an expansible member having one part connected with the valve stem to move with it and the other part connected with the body and subjected on one side to the pressure of the atmosphere and on the other side to the pressure within the body on the inlet side to open the valve, a weighted lever connected to the body and operating upon the valve stem to close the valve against the inlet pressure acting upon the expansible member, a spring connected with the lever and coöperating with the weight thereof for closing the valve, and means to adjust the tension of the spring.

5. In a device of the character stated, the combination of a body having inlet and outlet ports and a thoroughfare between them, a valve to control the thoroughfare having a stem extending to the outside of the case, an expansible member having one part connected with the valve stem to move with it and the other part connected with the body and subjected on one side to the pressure of the atmosphere and on the other side to the pressure within the body on the inlet side to open the valve, a weighted lever connected to the body and operating upon the valve stem to close the valve against the inlet pressure acting upon the expansible member, a spring connected with the lever and coöperating with the weight thereof for closing the valve, and means to change the point of connection of the spring with the lever.

6. In a device of the character stated, the combination of the body having inlet and outlet ports, and a thoroughfare between them, a substantially balanced valve device controlling the thoroughfare, a valve stem for operating the valve device extending to the outside of the body, a disk secured to the stem, a bellows structure having one end secured to the disk and the other end to the body and its interior in communication with the outside atmosphere, said disk and bellows acted upon by the inlet pressure to operate the valve and stem in opening the valve, and mechanically applied pressure devices exterior to the body for applying pressure upon the stem to close the valve in opposition to the pressure upon the bellows to open it.

7. In a device of the character stated, the combination of the body having inlet and outlet ports, and a thoroughfare between them, a substantially balanced valve device controlling the thoroughfare, a valve stem for operating the valve device extending to the outside of the body, a disk secured to the stem, a bellows structure having one end secured to the disk and the other end to the body and its interior in communication with the outside atmosphere said disk and bellows acted upon by the inlet pressure to operate the valve and stem in opening the

valve, mechanically applied pressure devices exterior to the body for applying pressure upon the stem to close the valve in opposition to the pressure upon the bellows to open it, and means to adjust the mechanically applied pressure.

8. In a device of the character stated, the combination of the body having inlet and outlet ports, and a thoroughfare between them, a substantially balanced valve device controlling the thoroughfare, a valve stem for operating the valve device extending to the outside of the body, a disk secured to the stem, a bellows structure having one end secured to the disk and the other end to the body and its interior in communication with the outside atmosphere said disk and bellows acted upon by the inlet pressure to operate the valve and stem in opening the valve, mechanically applied pressure devices exterior to the body for applying pressure upon the stem to close the valve in opposition to the pressure upon the bellows to open it, and means to adjust the mechanically applied pressure comprising a lever having an adjustable weight.

9. In a device of the character stated, the combination of the body having inlet and outlet ports, and a thoroughfare between them, a substantially balanced valve device controlling the thoroughfare, a valve stem for operating the valve device extending to the outside of the body, a disk secured to the stem, a bellows structure having one end secured to the disk and the other end to the body and its interior in communication with the outside atmosphere said disk and bellows acted upon by the inlet pressure to operate the valve and stem in opening the valve, mechanically applied pressure devices exterior to the body for applying pressure upon the stem to close the valve in opposition to the pressure upon the bellows to open it, and means to adjust the mechanically applied pressure comprising a weighted lever and a spring device connected with the lever and coöperating with the weight thereof.

10. In a device of the character stated, the combination of the body having inlet and outlet ports, and a thoroughfare between them, a substantially balanced valve device controlling the thoroughfare, a valve stem for operating the valve device extending to the outside of the body, a disk secured to the stem, a bellows structure having one end secured to the disk and the other end to the body and its interior in communication with the outside atmosphere said disk and bellows acted upon by the inlet pressure to operate the valve and stem in opening the valve, mechanically applied pressure devices exterior to the body for applying pressure upon the stem to close the valve in opposition to the pressure upon the bellows to open it, means to adjust the mechanically applied

pressure comprising a weighted lever and a spring device connected with the lever and coöperating with the weight thereof, and means to adjust the tension of the said 5 spring.

11. In a device of the character stated, the combination of a body having inlet and outlet ports, and a thoroughfare between them, a valve device controlling the thoroughfare and having a stem extending to the 10 outside of the body, a disk secured to the stem, a bellows surrounding the stem and having one end secured to the perimeter of the disk, a second disk secured to the other

end of the bellows and clamped to the body 15 whereby the interior of the bellows is in communication with the atmosphere and the outside of the bellows and first-mentioned disk subject to the pressure within the body on the inlet side of the valve, and mechanical 20 means outside of the body for applying pressure upon the valve stem to close the valve.

In testimony of which invention, I hereunto set my hand.

FRANCIS H. MONTREUIL.
